MINE CAR COUPLING BAR

Paul Laukus, Sr., North Huntington Township,
Westmoreland County, Pa., assignor to Irwin
Foundry and Mine Car Company, Irwin, Pa.,
a corporation of Pennsylvania

Application October 15, 1946, Serial No. 703,419

4 Claims. (Cl. 213—78)

1

This invention relates to coupling bars for mine cars used as a safety measure, in addition to the usual types of coupling, and especially automatic couplers, and also useful during towing and re-railing operations.

The principal object of the invention is to provide a coupling bar which is inexpensive to manufacture, easily attached to mine cars, durable, and which tends to avoid injury to workmen in and about mines.

Where mine cars are taken into or removed from a mine by way of a slope or where numerous grades are encountered, there is always the danger of coupler failure, thereby causing a hazard to mine workmen and mine property. To guard against this, it has been common practice to supplement the usual types of couplers with safety chains detachably connected to adjacent cars, at their ends. These chains are not drawn taut, unless the cars start to separate due to coupler failure. It has been common practice to secure eye members to the car bodies at their ends and adjacent their sides for detachably receiving the ends of the safety chains. In the past accidents have occurred due to workmen using these projecting eye members as steps when getting into or out of the cars or as platforms, and slipping from same while the cars are in motion. It is another object of the invention to so locate the coupling bars with respect to the car body ends, that the eye portions cannot well be used as steps or platforms and thus tend to induce workmen not to get on and off cars while in motion and not to ride on the cars between the ends of adjacent cars.

Other objects and advantages of the invention will appear in the following description of the preferred embodiment of the invention, taken in connection with the accompanying drawings, forming a part of this specification, and in which drawings:

Fig. 1 is a perspective view of an elongate piece of metal of right angular cross section, providing flanges, from which a coupling bar made according to the present invention may be fabricated.

Fig. 2 is perspective view of the piece of metal shown in Fig. 1 drilled with holes in one of the flanges, for attachment of the coupling bar to the car, and having the other flange cut transversely from its free edge to its juncture with the first mentioned flange so as to divide the second mentioned flange into a major intermediate portion and two minor end portions.

2

Fig. 3 is a perspective view of the completed coupling bar, inverted to disclose details.

Figs. 4 and 5 are fragmentary side elevational and plan views, respectively, showing a mine car equipped with the coupling bar.

Fig. 6 is a detailed view, partly in plan and partly in horizontal section showing the coupling bar attached to mine car body carried elements.

Fig. 7 is an enlarged sectional view on the line 10 7—7 of Fig. 6.

In the drawings, portions of a typical mine car of large capacity, such as is illustrated in my co-pending application relating to railway car truck and body mountings, filed March 28, 1947, Serial No. 737,755, are shown, comprising a body 10 including an end wall 11, side walls 12, and a bottom 13 joined to the lower portions of the end and side walls, the body being mounted on a truck 14; a coupler housing 15 including spaced channel members 16 extending longitudinally of and beneath the bottom 13 symmetrically disposed to each side thereof, these members 16 extending to or adjacent the plane of the car end wall 11; and a coupler 18 comprising a coupler head 19, coupler shank 20 therefor swingably mounted between the housing members 16 and a wear plate 21 secured to the housing 15 in any suitable manner and extending outwardly from the lower portion of the housing 15 at the end of the car, the shank 20 bearing upon the wear plate 21. It is understood that this is a conventional construction and arrangements of parts of a mine car and are shown merely by way of example.

To this, or any similar construction of mine car, I apply a coupling bar 22 for supplemental coupling of adjacent cars in a train as by use of a chain or other flexible member, or for use in towing or re-railing of the car as by a tow line, and which may also be used to cooperate with brace means 23 associated with a coupling bar 22 and wear plate 21.

The coupling bar is preferably formed of a single piece of metal and fabricated from sheet material or rolled metal stock shaped to provide a first flange 24, and a second flange 25 in right angular relation to one another at a juncture portion 26 as shown in Fig. 1. It is preferred to fabricate and shape this stock so that the flange 24 provides a major intermediate flange portion 27, and from minor end portions 28 of the flange 24, shown in Fig. 2, parts of terminal eye portions 29 at the ends of the second flange 25, as shown in Fig. 3. This is preferably accomplished by providing two slits 30 in flange 24 extending from its free edge to the juncture portion 26,

the slits being spaced apart sufficient to leave the major intermediate flange portion 27, then heating the stock to a forging temperature and bending the minor end portions 28 at the juncture portion 26, so as to lie upon the second flange 25 and parallel to the plane thereof, and then hammering and shaping the stock to provide the terminal eye portions 29 which each have a hole 31 therein made by a mandrel held by a hammer, not shown in the drawings.

This method of fabricating the coupling bar is disclosed and claimed in my copending application filed November 30, 1948, Serial No. 62,616, provides a unit, light in weight, but of great strength to resist pull, shock and torsional strains or stresses, and to also assist in bracing the wear plate 21. Suitable holes 32 may also be provided in the flange 25 for securing the coupling bar to body carried parts of the mine car.

In the example shown, the coupling bar is secured transversally to the undersides of the members 16, with the flange 25, engaging therebeneath, as by rivets 33, and close to or engaging the rear portion of the wear plate 21. The coupling bar is preferably of such length as to span the space between the members 16, extend under the latter and dispose the eye portions 29 just outside the planes of the members 16 as shown in Fig. 5 where they are located inwardly of and remote from the planes of the side walls 12 of the car body 10.

The brace means 23 may comprise one or more gusset plates 34, welded to the underside of wear plate 21 and depending intermediate flange portion 27 as shown in Figs. 4 and 5. It is understood that the eye portions may receive hooks of chains or other flexible members used as supplemental coupling means, or of tow bars, chains or cables, used in towing or re-railing.

In specifying that the eye portions of the coupling bar are located inwardly of and remote from the planes of the side walls 12 of the car body 10, reference is had to locations where the eye portions are inaccessible to workmen as steps for mounting or descending from a coupled car, and in contradistinction to the common practice of securing individual eye members adjacent to the planes of the side walls 12 where they are frequently used as steps or platforms.

It will be noted from Fig. 7 that if the coupling bar is made in accordance with the above described method, a portion 35 of each terminal eye is material from the juncture portion 26 of the original stock, and is located where the pull on the eye is most apt to come if there is main coupler failure or during towing or re-railing operations. This portion 35 is well adapted to resist distortion or fracture.

While I have disclosed the preferred embodiment of the invention it is to be understood that changes may be made in details, proportions, etc., without departing from the spirit of the invention as defined in the following claims.

I claim:

1. In combination with a mine car including a body provided with an end wall, side walls and a bottom joined to the lower portions of said end and side walls, of a coupling bar rigid with the

car body, extending transversally of and beneath the car body adjacent the plane of the end wall thereof, said coupling bar provided with terminal eye portions located inwardly of and remote from the planes of the car body side walls and in spaced apart relation to said end wall and bottom.

2. In combination with a mine car including a body provided with an end wall, a bottom and spaced members beneath the bottom and extending longitudinally of the body to adjacent the plane of said end wall, of a coupling bar secured to the under sides of said spaced members transversally thereof beneath the end of the car body, said bar providing with terminal eye portions laterally outside the planes of said longitudinally spaced apart members of the car body and in spaced apart relation to said end wall and bottom.

3. In combination with a mine car including a body provided with an end wall and a bottom, a coupling housing including spaced members beneath the car bottom extending longitudinally thereof, and a coupling including a coupler shank accommodated between said spaced members of the housing, of a coupling bar for use in supplemental coupling of cars, secured to the under sides of said spaced housing members, transversally thereof beneath the end of the car body, said bar provided with terminal eye portions laterally outside the planes of said spaced housing members and in spaced apart relation to said end wall and bottom.

4. A mine car including a body provided with an end wall and a bottom, a coupling housing including spaced members beneath the car bottom extending longitudinally thereof, a coupling including a coupler shank swingably mounted between said housing members, and a wear plate beneath and upon which said shank engages, located adjacent the ends of said housing members, a coupling bar of angular cross section for use in supplemental coupling of cars, located transversally beneath said housing members and including an upper horizontal flange secured to the latter, a lower vertical flange beneath said wear plate and terminal eye portions on said upper flange outside the planes of said spaced housing members and in spaced apart relation to said end wall and bottom, and brace means between the underside of said wear plate and said vertical flange of the coupling bar.

PAUL LAUKUS, SR.
